AIR-HEATING FURNACE WITH FORCED
FLOW AIR CIRCULATING MEANS

Peter Kephart Russell, Shippensburg, Pa.

Application May 20, 1949, Serial No. 94,440

3 Claims. (Cl. 126—110)

1

This invention relates to a heating device, and more particularly to a heating unit embodying an oil burner and an air-circulating fan.

It is an object of this invention to provide a heating and cooling air-circulating device of the kind to be more particularly described hereinafter, having an air-circulating fan mounted above the heater body and directed toward the upper end of the heater for moving the heated air, in the immediate vicinity of the heater top, in any selected or desired direction.

Another object of this invention is to provide a heater of this kind having a novel burner and burner arrangement in relation to the air draft entering the burner. The burner is connected to an upwardly-directed air inlet draft and below a baffle or damper in the air-intake line for receiving air as it is moved from the cold air inlet end of the burner to the warm or heated nozzle end.

A further object of this invention is to provide a novel burner element for an oil burner of this kind formed for efficient and economical fuel consumption.

With the above and other objects in view, my invention consists in the arrangement, combination and details of construction disclosed in the drawings and specification, and then more particularly pointed out in the appended claims.

In the drawings:

Figure 1 is a front elevation, partly broken away and partly in section, of a hot and cold air-circulating device constructed according to an embodiment of my invention;

Figure 2 is a fragmentary side elevation of the upper end of the circulator;

Figure 3 is a transverse section taken on the line 3—3 of Figure 1;

Figure 4 is a fragmentary perspective view of the burner end of the fuel burner shown in Figures 1 and 2;

Figure 5 is a fragmentary detail section taken on the line 5—5 of Figure 1;

Figure 6 is a perspective view of the burner end of a modified form of burner;

Figure 7 is a side elevation, partly broken away and partly in section, of the modified burner shown in Figure 6.

Referring to the drawings, the numeral 10 designates generally a hot and cold air-circulating device constructed according to an embodiment of this invention. The device 10 is formed with an upwardly-opening, hollow body 11 formed of metal or other suitable material. The bottom open end of the body 11 is fixed to or otherwise

2

suitably secured on a base or bottom member 12 which is adapted to be suitably positioned and fastened to a floor 14 or other suitable supporting device. The body 11 is open at the upper end and a cover or closure member 15 is adapted to be removably secured on the upper end of the body for closing the upper open end thereof. The cover 15 is formed with a convex top wall 16 having a marginal flange 17 on the lower or bottom edge thereof. The marginal flange 17 is adapted to be frictionally engaged about the outer side of the upper end of the body 11 for frictionally securing the cover 15 thereto.

A fan or blower element 18 is adapted to be positioned below the heater body 11, as below the floor 14, as shown in Figure 1 of the drawings. An air duct 19 is connected to the blower or fan 18 and extends upwardly from the blower along the length of the body 11 adjacent thereto. The fan 18 is positioned at the lower end of the air duct 19 for blowing the air upwardly, thereby providing an up-draft for conducting or leading air to the burner element 20 within the body 11.

A damper 21 is rockably supported within the air duct 19 and includes a flat disc 22 for disposition transversely of the duct 19, the plate 22 being hingedly mounted on a transverse hinge bar 24 which is pivotally mounted in the side walls of the duct 19 transversely thereof. A crank or handle 25 is fixed on the other end of the hinge or bar 24 or selectively positioning the damper 21 in a selected angular position transversely of the tube 19 for directing a certain amount of air from the up-draft duct 19 to the burner 20. The damper 21 is positioned in the tube 19 above the lower end of the heater body 11 and a fuel-conducting tube 26 is adapted to be connected into one side wall of the duct 19 below the damper 21.

The elongated tube 26 is fixed at one end to the duct 19 on one side thereof and extends substantially horizontally into the heater 11 at the lower end thereof. The extreme inner end of the tube 26 is formed with an elongated horizontally-extending slot 27 along the length thereof, the slot or opening 27 constituting the burner opening or point at which the fuel within the tube 26 may be ignited and burned. The extreme inner end 28 of the tube 26 closes the tube 50 at the inner end thereof so that the fuel and air entering the tube 26 and being moved along the length thereof will pass outwardly through the slot 27 in a substantially horizontal direction transversely of the longitudinal axis or length of the tube 26.

A fuel oil tank 29 is suitably positioned outside of the heater body 11 and may be aptly supported thereon by a bracket 30. A fuel-conducting line 31 is connected at one end to the bottom of the fuel tank 29 and at the other end to a fuel-control valve 32. The fuel-control valve 32 is connected to the fuel inlet tube 26 between the heater body 11 and the air duct 19, as clearly shown in Figure 1 of the drawings. The control valve 32 will suitably control the amount of fluid passing from the tank 29 to the burner 20.

A suitable door or closure member 35 is swingably mounted in one wall of the heater housing 11 adjacent the lower end thereof to provide suitable access to the interior of the housing 11 and to the burner 20 enclosed thereon. Suitable air-inlet openings 36 are formed in the lower end of the wall of the body or housing 11 opposite from the entrance of the tube 26 through the wall 11, substantially in alignment with the axis of the tube 26, to provide for the proper combustion of the fuel at the nozzle opening 27.

In the use and operation of the heater described above, with the blower 18 in operation, the damper 25 is properly set at a desired angle relative to the axis of the duct 19 for forcing a desired amount of air into the heater body 11 through the tube 26. The valve 34 connected to the tube 26 between the duct 19 and body 11 will provide a suitable fine control for the admission of air to the burner 20 and the valve 32 will provide for the control of oil from the oil supply reservoir 29. As the tube 26 is inclined slightly downwardly and inwardly so that the fluid entering the tube 26 at the valve 32 will substantially flow down along the lower side thereof into the heater 11, the oil at the burner opening 27 may be ignited, and the ignition of the oil at the burner 20 will provide for the suitable heating of the cover member 15. A suitable exhaust tube 37 is connected to the body 11 intermediate the length thereof above the burner 20 to provide for the suitable discharge of the burned gases within the body 11.

As the top of the body 11, the cover 15, is the focal point of the heated gases within the body 11, there is provided a fan or blower 38 which is directed toward the convex cover 15 for blowing the heated air in a selected or desired direction.

A frame 39 is fixed to the upper end of the tank 11 for supporting the blower or motor 38 thereon and may be suitably supported on the body 11 in any selected relative position for blowing the air in the immediate vicinity of the cover 15 in any selected direction. A ring 40 is engaged about the body 11 adjacent the upper end thereof and below the cover 15. The ring 40 is adapted to be slidably and rotatably secured on the body 11 to be fixed in any selected rotated position relative to the body by means of securing elements or bolts 49 rotatably supported in openings formed in the ring 40 and engaging the shell 11. A pair of outwardly-directed arms 41 and 42 are fixed on the opposite sides of the ring 40 and the arms 44 and 45, formed integrally with the arms 41 and 42, respectively, extend upwardly substantially parallel to the axis of the cylindrical body 11. A connecting bar 46 is secured to the extreme upper ends of the upwardly-extending bars 44 and 45 and is preferably disposed substantially across the diameter of the body 11. The arms 41, 42, 44, 45 and 46 together constitute a loop 47 engaging about the upper end of the tank 11 and cover 15 in such a manner that each of the arms, or the entire loop, is spaced away from the cover

15 and the blower 38 which is carried by the loop 47 may be positioned at any selected angle directed at the cover 15. Suitable bolts 48 secure the loop 47 to the anchor ring 40 and other bolts 5

49 engage through the ring 40 and clampingly engage the outer surface of the body 11 for fixedly securing the ring 40 and loop 47 in any selected angular position relative to the vertical axis of the body 11.

10 The arms 44, 45 and 46 are formed with a plurality of longitudinally-spaced-apart apertures 50 along the length thereof, and a bracket 51 is adapted to be fixed in a selected pair of apertures 50. The blower or fan 38 is fixedly carried by the bracket 51 so that the selected positioning of the bracket 51 along the length of the loop 47 will position the blower 38 at a selected angular relation to the cover 15. Preferably, the blower 38 will be disposed in such a manner that the air blowing from the blower 38 toward the cover 15 will substantially engage the cover 15 tangent thereto for blowing the heated air transversely of the heater body 11 in any selected horizontal, or downwardly-directed, direction.

15 In Figures 6 and 7 of the drawings, there is shown a modified form of burner 52 for use in place of the burner 20 described above. The burner 52 is formed of an elongated tube 54 for connection to the air-draft duct 19 in the same manner as the connection of the tube 26. A transverse tube 55 is fixed to the front end of the tube 54 diametrically thereof, and extends outwardly beyond the side edges. The transverse head 55 is formed with an elongated, horizontal slot 56 opening at the forward end of the tube 54. The elongated slot 56 constitutes the burner opening through which the gases and oils being burned by the burner 52 will pass during the process of combustion. The slot or opening 56 is disposed in a horizontal plane and opens forwardly at the forward inner end of the tube 54.

20 I do not mean to confine myself to the exact details of construction herein disclosed, but claim all variations falling within the purview of the appended claims.

25 I claim:

1. An air-heating and circulating device comprising a hollow metal open-ended shell having one end adapted to be sealingly supported upon the floor of a room, a cover closing the other open end of said shell, a burner positioned within said shell adjacent said floor for converting a combustible mixture into heated products of combustion, means exteriorly of said shell and operatively connected to said burner for introducing a combustible mixture to said burner, a flue positioned exteriorly of said shell and connected to said shell intermediate the top and bottom for withdrawing the products of combustion from said shell, an upstanding loop provided with separated ends positioned adjacent to and surrounding the top of said shell and having its separated ends secured to said shell, and a rotatable fan positioned within said loop above and spaced from the top of said shell and supported on said loop for causing circulation of the heated air in the region externally of and about the cover of said shell.

2. An air-heating and circulating device comprising a hollow metal open-ended shell having one end adapted to be sealingly supported upon the floor of a room, a cover closing the other open end of said shell, a burner positioned within said shell adjacent said floor for converting a combustible mixture into heated products of

combustion, means exteriorly of said shell and operatively connected to said burner for introducing a combustible mixture to said burner, a flue positioned exteriorly of said shell and connected to said shell intermediate the top and bottom for withdrawing the products of combustion from said shell, a ring positioned exteriorly of said shell adjacent to and spaced from said cover and supported on said shell for sliding longitudinal movement with respect to said shell, an upstanding loop provided with separated ends positioned adjacent to and surrounding the top of said shell and having its separated ends secured to said ring, and a rotatable fan positioned within said loop above and spaced from the top of said shell with the fan facing the top of said shell and supported on said loop for causing circulation of the heated air in the region externally of and about the cover of said shell.

3. An air-heating and circulating device comprising a hollow metal open-ended shell having one end adapted to be sealingly supported upon the floor of a room, a cover closing the other open end of said shell, a burner positioned within said shell adjacent said floor for converting a combustible mixture into heated products of combustion, means exteriorly of said shell and operatively connected to said burner for introducing a combustible mixture to said burner, a flue positioned exteriorly of said shell and connected to said shell intermediate the top and bottom for withdrawing the products of combustion from said shell, a ring positioned exteriorly

5 of said shell adjacent to and spaced from said cover and supported on said shell for sliding longitudinal movement with respect to said shell, said ring being provided with a plurality of spaced openings therearound, securing elements rotatably supported in said openings and engaging said shell for securing said ring to said shell, an upstanding loop provided with separated ends positioned adjacent to and surrounding the top of said shell and having its separated ends secured to said ring, and a rotatable fan positioned within said loop above and spaced from the top of said shell with the fan facing the top of said shell and supported on said loop for causing circulation of the heated air in the region externally of and about the cover of said shell.

PETER KEPHART RUSSELL.
